HAROLD F. PARISH, OF BROOKLYN, NEW YORK, ASSIGNOR TO GRINDEN ART METAL COMPANY, OF BROOKLYN, NEW YORK, A CORPORATION OF NEW YORK.

SAFETY MECHANISM FOR POWER-OPERATED DOORS.

1,217,053.

Specification of Letters Patent. Patented Feb. 20, 1917.

Application filed June 9, 1914. Serial No. 844,053.

To all whom it may concern:

Be it known that I, HAROLD F. PARISH, a citizen of the United States of America, and residing in the borough of Brooklyn, 5 in the county of Kings and State of New York, have invented a certain new and Improved Safety Mechanism for Power-Operated Doors, of which the following is a specification.

10 My invention relates to a safety mechanism for power operated doors and the object of my invention is to provide electrically controlled means for rendering the door operating mechanism inoperative in 15 case the door meets an obstruction during its closing movement and particularly should the obstruction occur as the door nears its fully closed position.

In the accompanying drawings, 20 Figure 1 is a broken side elevation of a car door showing my invention applied thereto in one form;

Fig. 2 is a vertical section through a door showing my invention applied thereto in a 25 second form;

Fig. 3 is a cross section of a detail of the latter;

Fig. 4 is a partial perspective of a door showing still another method of applying 30 my invention thereto;

Fig. 5 is a plan of a detail of the latter;

Figs. 6 and 7 are side elevation and plan respectively of another detail of this modification; and

Fig. 8 is a perspective of a detail of a further modification.

Referring first to the construction shown in Fig. 1, the car door 10, supported as usual upon a rail 11 by trolleys 12, may be opened 40 or shut by means of a rod 13 secured at the rear edge of the door and provided at one end with a piston 14 working in cylinder 15. Fluid pressure—for example, compressed air—is supplied to one face of the piston 45 14 through pipe 16 to drive the piston in a direction to open the door, while the air is admitted through pipes 17^a and 17^b to the other face of the piston, to drive the latter in a direction to close the 50 door. The supply of air to the pipes 16 and 17^b is regulated in any suitable way (not shown) controlled by the conductor of the car. Pipe 17^a opens into a valve chamber 18 in which is arranged a plunger valve having 55 two heads 19 and 20 spaced apart on the stem

21. In the normal position of the valve the head 19 lies in such position that a passage is open through the valve chamber 18 to the supply pipe 17^b, while the head 20 closes the port opening to an exhaust pipe 17^c. The 60 valve is operated by electromagnetic means. For this purpose, the upper end of the valve stem carries a solenoid core 22, which, upon the energization of the winding 23, pulls the valve up into such position that the supply 65 pipe 17^b is closed by the head 19, while the pipe 17^a remains open to the valve chamber and now communicates with the exhaust pipe 17^c, opened by the rise of the head 20, so that in this position of the valve the compressed air in the cylinder 15 exhausts 70 through pipe 17^c. The closing movement of the door is thus obviously halted.

The electromagnet winding 23 is connected in any suitable way with a source of electrical energy, at one end through a wire 24, and at the other end through wire 25 which leads to a bar 26 embedded in insulation 27. A second bar 28 is also embedded in the insulation and spaced from the bar 26. Bar 80 28 is connected to the conductor 29 which leads through the normally closed switch 30 and fuse 31 to the second line wire 32. The two bars 26 and 28 are rigidly supported in any suitable way upon the car body and 85 extend into the hollow door 10. At their point of entry I arrange upon the door the two insulated brushes 33 and 34, or other suitable contacts. One brush 33 is electrically connected through conductor 35 with terminals 36 at the front edge of the door and lying within the channel formed to receive the spring-pressed buffer 37. The brush 34 is connected through conductor 38, with terminals 39 arranged to coöperate 90 with the spring terminals 36. In the normal position of the buffer 37 the spring terminals 36 are out of contact with the stationary terminals 39. Upon the depression of the buffer 37, however, as by striking an obstruction, (e. g. an arm, leg, etc., of a passenger) the spring terminal 36 is engaged by the insulating block 40 carried on the inner face 95 of the buffer and is pressed thereby into engagement with the terminal 39 and completes the circuit through the solenoid winding 23. The resulting energization of the latter lifts the plunger valve to a position in which the pipe 17^a exhausts through the branch 17^c, while the flow of compressed air 100 110

through pipe 17^b is cut off by the valve head 19.

The closing motion of the door is thus halted until the obstruction is removed, 5 whereupon the buffer 37 is pressed outward by the springs 41 and the contact between terminals 36 and 39 broken. Inasmuch as this deenergizes the solenoid 23, the valve drops by gravity to its normal position and 10 the fluid pressure is again admitted through 17^a to the cylinder 15, completing the closure of the door. Obviously the return of the valves to normal position may be accelerated by a suitably arranged spring, if 15 desired.

It is perfectly obvious that the door could be halted at any point during its closing travel, if desired, by exposing the bars 26 and 28 throughout their length to contact 20 with the brushes 33 and 34. The only point at which danger of injury to the passenger who obstructs the door occurs is that at 25 which the door is nearly closed and the leg or arm is in danger of being caught between the door and the jamb. Consequently the bars 26 and 28 are insulated for the major portion of their length from contact with the brushes 33 and 34 so that even if the buffer 37 should be depressed during the 30 first portion of the closing travel of the door, it has no effect upon closing movement and it is not until the door is nearly closed that the bars 26 and 28 are engaged by the brushes 33 and 34 and that the mechanism is in a condition in which the solenoid 35 circuit could be closed by the depression of the buffer.

Similarly, the brushes 33, 34 run off the bars 26, 28 and onto the insulation 27 just 40 before the door comes into contact with the jamb. The depression of the buffer by its impact against the jamb under the closing force thus does not result in the cutting out of the closing pressure as it would were the 45 brushes and bars still in contact. It is thus seen that the exposed portion α of the bars 26, 28 conforms in length and position to the danger-zone travel of the door.

While I have shown the solenoid operating 50 a controlling valve in a pneumatically closed door, it will be readily understood that it could equally well open a clutch or operate any suitable disconnecting mechanism in a mechanically operated closing device.

In the arrangement shown in Figs. 2 and 55 3 the door carries on its rear edge a tube 42 provided near its outer end with plates 43 and 44 separated by insulation 45 from the 60 tube and coöperating with terminals 46 and 47 to which the wires 25 and 29 respectively are connected. Thus when the door has reached a position substantially corresponding to that shown in Fig. 1, the contacts 46 65 and 47, mounted in stationary position on

the car body, ride up on the plates 43 and 44 and make electrical contact therewith, thus substantially corresponding in their action to the engagement of the contacts 33 and 34 with the bars 26 and 28 of Fig. 1. 70 To complete the circuit between plates 43 and 44 I provide a rod 48 attached at one end to the buffer 37 (Fig. 1) and held by the latter normally in the position shown in Fig. 2. In this position a metal ring 49, 75 supported on the rod 48 through an insulating bushing 50, is spaced from the lugs 51 and 52 which project into the tube 42 from the respective plates 43 and 44. Should the buffer 37 be now depressed, the rod 48 is 80 driven backward and the ring 49 pressed against the lugs 51, 52, thus completing the solenoid circuit and shifting the valve to the position in which the compressed air is 85 cut off from the power cylinder 15 through pipe 17^b, whereupon pipe 17^a is opened to the exhaust 17. Obviously upon the removal of the obstruction, the outward movement of the buffer breaks the solenoid circuit and the valve returns to normal position. Pins 53 and 54 may be supplied, if 90 desired, to hold the brushes 46 and 47 normally out of contact with the tube 42 or the casing 45 or insulation may be carried the full length of the tube, if desired. 95

In the modification shown in Figs. 4 to 7, my invention is adapted to the construction shown in the patent to Rowntree *et al* numbered 1,001,990. In like manner as there shown, the rod 55 rocks the bell crank lever 56 upon the depression of the buffer 37 and forces backward the rod 57 which projects through the rear edge of the door. A saddle 58, embracing a curved bar 59 on the rear edge of the door, is carried at one 100 end of the rocker bar 60. The engagement between the saddle and the curved bar 59 results in the turning of the rocker bar 60 on its axis, on the longitudinal displacement of the rod 57 with relation to the door. I 105 utilize this movement of the rocker bar 60 to secure the engagement between the two contacts 61 and 62 connected respectively to the wires 29 and 25 of the solenoid circuit. To this end the contact 62 is mounted in 110 stationary position, while the contact 61 is carried upon the plate 63. The latter is held against longitudinal movement by the frame 64, but is free to rock into engagement with the contact 62. Downwardly projecting 115 flanges 65, on the plate 63, form a guide for the outer end of the rod 60 and the latter is provided with a key 66 for a portion of its length which engages in a key-way formed in the flanges 65. The key 66 is located upon 120 the rod 60 in such position that it does not engage its keyway in the flanges 65 until the door has reached approximately the position shown in Fig. 1. Consequently an obstruction to the door which occurs in 125 130

vance of this position would not rock the contact 61 into engagement with the contact 62. Whereas, if the door had reached the position shown in Fig. 1 and the key 66 had 5 become engaged in the key-way 67, the depression of the buffer 37 would result in the oscillation of the plate 63 and move the contact 61 into circuit-closing position with relation to contact 62. A spring 68 may be arranged beneath one end of the plate 63 to 10 accelerate its return upon the release of the buffer. To insure the engagement between the key 66 and its key-way 67, the edges of the latter may be beveled outward, as shown 15 in Figs. 6 and 7.

In the modification shown in Fig. 8, I have assumed that the door is electrically closed through any suitable means (not shown). The circuit for operating the closing mechanism is led through terminals 69 and 70, normally connected by the switch piece 71, carried on a lever 72 to which the stem 73 of the solenoid core 74 is connected. Upon the energization of the solenoid 20 through any one of the mechanisms above described, the core 74 is lifted and carries with it the switch piece 71, thus breaking the circuit through the terminals 69 and 70 and de-energizing the electrically operated 25 closing mechanism. As soon as the solenoid circuit is broken by the return of the buffer to normal position, the switch 71 drops between the terminals 69 and 70 and again completes the circuit of the closing mechanism. 30

Various other applications of the invention will readily suggest themselves and I do not limit my invention to the details shown and described.

40 I claim as my invention:—

1. The combination with a door of means for closing the door, electrically controlled means for halting the door in its closing travel and means operated by the impact of the door against an obstruction during only 45 the latter portion of its closing movement for completing the controlling circuit.

2. The combination with a door of means for closing the door, electrically controlled 50 means for halting the door in its closing travel, a pair of contacts in the controlling circuit, one of said contacts being carried by the door and the other being stationary with relation thereto, said contacts being automatically closed only during the approach of the door to its jamb, together with a pair 55 of normally open contacts also in the controlling circuit and means operated by the impact of the door against an obstruction on its closing movement for completing the circuit through 60 said normally open contacts.

3. The combination with a door of means for closing the door, electrically controlled 65 means for rendering said closing means in-

operative and means operated by the impact of the door against an obstruction during only the latter portion of its closing movement for completing the controlling circuit.

4. The combination with a door of means 70 for closing the door, electrically controlled means for rendering said closing means inoperative and means operated by the impact of the door against an obstruction during only the latter portion of its closing movement for completing the controlling circuit. 75

5. The combination with a sliding door of means for closing the door, and electrically controlled means for rendering said closing means 80 inoperative, said door halting means comprising a stationary contact in the controlling circuit, a co-operating contact carried by the door and reciprocating therewith, said contacts automatically closing during only the latter portion of the closing travel 85 of the door, a pair of normally open contacts also in said circuit and a yieldable buffer at the edge of said door and means operated by the displacement of said buffer with relation to said door for closing said 90 normally open contacts.

6. The combination with a door, a yielding member carried at the front edge of the door, means for closing the door and electrically controlled means for halting the door 95 in its closing travel, said door halting means comprising an electric circuit and co-operating contacts therein normally open but adapted to be brought into electrical connection by the movement of said yieldable member with relation to the door on impact against an obstruction together with a second pair of co-operating contacts in said circuit, one of said contacts moving with the door and the other being stationary with relation thereto, the circuit through said last mentioned pair of contacts being automatically closed during only the latter portion of the closing travel of the door. 105

7. The combination with a door, a yielding member carried at the front edge of the door, means for closing the door and electrically controlled means for rendering said closing means inoperative during its closing travel, said electrically controlled means 110 comprising an electric circuit and co-operating contacts therein normally open but adapted to be brought into electrical connection by the movement of said yieldable member with relation to the door on impact against an obstruction together with a second pair of co-operating contacts in said circuit, one of said contacts moving with the door and the other being stationary with relation thereto, the circuit through said last mentioned pair of contacts being automatically closed during only the latter portion of the closing travel of the door. 115

8. The combination with a door, of means for closing the door, and means for halting 120

the door in its closing travel, said means comprising an electric circuit, an electro-magnetic means therein for operating the door-halting means, normally open contacts 5 in said circuit and means operated by the impact of the door against an obstruction on its closing movement for bringing said contacts into electrical engagement to complete the circuit together with a second pair of co-operating contacts in said circuit, one of said contacts moving with the door and the other being stationary with relation thereto, the circuit through said last mentioned pair of contacts being automatically closed during 10 only the latter portion of the closing travel of the door.

9. The combination with a door, of means for closing the door, and means for halting the door in its closing travel, said means comprising an electric circuit, an electro-magnet means therein for operating the door-halting means, normally open contacts 20 in said circuit and means operated by the impact of the door against an obstruction on its closing movement for bringing said contacts in electrical engagement to complete the circuit and breaking said electrical engagement on the removal of said obstruction, whereby the circuit is opened and the 25 door-halting means rendered inoperative together with a second pair of co-operating contacts in said circuit, one of said contacts moving with the door and the other being stationary with relation thereto, the circuit 30 through said last mentioned pair of contacts being automatically closed during only the latter portion of the closing travel of the door.

10. The combination with a door of a 40 spring-pressed yielding member carried at the front edge of the door, means for closing the door and electrically controlled means for halting the door in its closing travel, said door halting means comprising an electric circuit and co-operating contacts therein 45

normally open but adapted to be brought into electrical connection by the movement of said yieldable member with relation to the door on impact against an obstruction, said yieldable member separating said contacts again upon the return of said yieldable member to normal position after the removal of said obstruction together with a second pair of co-operating contacts in said circuit, one of said contacts moving with the 55 door and the other being stationary with relation thereto, the circuit through said last mentioned pair of contacts being automatically closed during only the latter portion of the closing travel of the door. 60

11. The combination with a door of a spring-pressed yielding member carried at the front edge of the door, means for closing the door and electrically controlled means for halting the door in its closing travel, 65 said door halting means comprising an electric circuit and co-operating contacts therein normally open but adapted to be brought automatically into electrical connection by the movement of said yieldable member with 70 relation to the door on impact against an obstruction, said yieldable member automatically separating said contacts again upon the return of said yieldable member to normal position after the removal of said obstruction together with a second pair of co-operating contacts in said circuit, one of said contacts moving with the door and the other being stationary with relation thereto, the circuit 75 through said last mentioned pair of contacts being automatically closed during only the latter portion of the closing travel of the door. 80

In testimony whereof I have signed my name to this specification, in the presence of two subscribing witnesses.
